HOISTING MECHANISM.

1-164617

Specification of Letters Patent. Patented Dec. 14, 1915.

Application filed January 14, 1907, Serial No. 352,319. Renewed November 9, 1912. Serial No. 730,495.

To all whom it may concern:

Be it known that I, ERBRIDGE S. COLLEY,
a citizen of the United States of America,
and a resident of Portland, Maine, have in-
5 ventioned certain new and useful Improvements
in Hoisting Mechanism, of which the fol-
lowing is a specification.

My invention relates to hoisting apparatus of the class used for unloading coal barges, dredging and the like, which is commonly embodied in a tower-like structure and in which the bucket is raised and lowered and opened and closed by two bucket ropes. The latter run first over the mast and thence over a support, such as a trolley, located on a horizontal boom and having a traversing movement thereon, and thence around main hoisting drums operated by a hoisting engine or other motor. In this class of devices, as heretofore constructed, the trolley is drawn outward by a rope wound on a trolley drum operated by a special trolley engine, and is drawn inward on the boom by the action of the main hoisting ropes which lead down from the mast head. These hoisting devices or "diggers" have commonly been operated by two men, one to handle the main drums and the main hoisting engine, and the other, called a "trolley man", who controlled the trolley engine and its drum. Each man has two vertical levers to handle, which levers are connected by mechanical means with the main drums and the trolley drum, respectively, and each has also a foot lever connected with the throttle valve of his respective engine. In manipulating the bucket and dropping it accurately into the hold of a vessel, the control being in the hands of two men who do not know each other's intentions, both delay and accidents are of constant occurrence because of the uncertainty at critical times and a conflict of effort by the operators. These buckets when loaded weigh from one to two tons or more and are handled very rapidly, and hence the accurate control of them is very desirable.

The object of the present invention is to provide means whereby one man can control the variety of controlling devices necessary, 50 doing away with the trolley man and converting the apparatus into a one-man digger or one-man tower.

The invention will be best understood by reference to the following description when taken in connection with the accompanying

illustration of one specific embodiment thereof, while its scope will be more particularly pointed out in the appended claims.

In the drawings: Figure 1 is a view diagrammatic in form, showing a coal hoisting apparatus equipped with one embodiment of the invention; Fig. 2 is a central, longitudinal section through one of the operating levers; Fig. 3 is a cross section on the line $y-y$ of Fig. 2; Fig. 4 is a horizontal section on the line $x-x$ of Fig. 2, with the valve omitted; Fig. 5 is a vertical, longitudinal section taken through the trolley drum; and Fig. 6 is a cross section on the line $x-x$ of Fig. 5 with additional details. 60 65 70

In Fig. 1 of the drawings, 1 represents the mast, 2 the boom, 3 the trolley, 4 the bucket, 5 the hoisting rope, 6 the bucket closing rope, and 7 the trolley rope for reversing the trolley on the boom. The main or bucket engine 8, herein of the pressure fluid type, has the connecting rod 9 connected to the main drum crank shaft 10 on which are mounted the main hoisting rope-winding drum 11 and the rope-winding drum 12 for operating the bucket closing rope 6. The friction on the main drum 11 is operated or controlled through the connecting rod 13, and the friction for the drum 12 is controlled through a similar connecting rod 14. 16 85 is a lever which connects the connecting rod 13 with the connecting rod 17, the latter being connected to one of the two friction controlling or operating hand levers A, A', while 15 is a lever connecting the connecting rods 14 and 18, the latter connecting with the remaining friction controlling or operating hand lever, the said levers A, A' being thereby directly and mechanically connected to control the frictions for the bucket 95 ropes, so that the operator can sensitively feel the grip or pull on the frictions at all times and thereby accurately gage and control the slippage. The trolley engine 26 also of the pressure fluid type has the connecting rod 27 connected to the crank disk 19 of the trolley rope winding drum 40 (Fig. 5). 100 21 is a lever controlling the band brake 44 (Figs. 5 and 6) and 23 a lever controlling the drum friction clutch 43 (Fig. 5). The throttle valve 28 of the trolley engine is operated by means of a cord or rope 29, the latter connected to a foot control element or lever 31 at the operator's stand. Means are provided for controlling the main hoist- 110

ing engine in the form of a throttle valve 33 connected through the cord 30 with a controlling device at the bucket operator's position in the form of the foot lever 32 connected to the cord 30.

In Figs. 5 and 6 are shown more in detail the construction of the well known trolley drum and means for controlling the same inserted for the better understanding 10 of my invention as hereafter set forth. Considering Figs. 5 and 6, 19 is the crank disk connecting with the connecting rod 27 of the trolley engine, 41 is the shaft on which the drum proper 40 slides and turns, 15 42 is the friction member which is keyed to the shaft, and 43 the conical friction surface on the end of the drum which acts against a corresponding surface on the friction member 42. 45 is a screw member 20 gaging a screw threaded recess in the shaft bearing 46, the screw member impinging against the end of the trolley drum and being turned by the lever 21 shown in Fig. 1. The band friction 44 surrounds one end of 25 the drum and this is controlled by the lever 23 (shown in Fig. 1) pivoted to a standard 23*. It will be readily understood that the lever 23 causes the friction band 44 to act to check the rotation of the trolley drum and 30 the lever 21 operates to turn the screw 45 and to press the same against the end of the drum, forcing the latter against the friction member and causing the drum to turn. Thus when the drum is to be used for pulling out 35 the trolley to the end of the boom, the friction band is released and the lever 21 operated to turn the screw and throw in the drum friction, thus causing the drum to wind up the trolley rope. When the 40 trolley is to run in, the drum friction and the band friction are both released and the latter is used to check the movement of the drum when the trolley reaches the right point. Each of the main hoisting drums is 45 provided with a friction clutch similar to that shown at 43 and 44 for the trolley drum and is operated by a suitable lever similar to lever 21, neither of the above parts being shown, these levers being connected to the 50 reach rods 17 and 18 in the usual manner.

The parts so far designated are old and well known in hoisting devices and with the above explanation need no further description to understand the application of my invention, the novel features of which will now be described. The operating levers A and A' which are connected to the connecting rods 55 17 and 18, respectively, are horizontally disposed at the operator's position side by side 60 with an intermediate space between and compounded so that a man can stand between them and by pressing down with each hand easily control the two drums. Combined with these are one or more members 65 or devices controlling the traverse of the

trolley, herein through the agency of compressed air, such members or devices being so connected to the friction controlling hand levers A, A' that the operator with the same hand with which he operates the 70 mechanically connected friction levers can operate a traversing control device, so that the coöperating movements of the bucket and its traversing support may be simultaneously controlled by the same operator. 75 Such traverse control members may be of any suitable form and construction, but herein they are preferably embodied in the form of grasping devices, one on each friction lever, and movable independently of 80 the latter. In the specific form of the invention herein shown, one grasping device is employed to control the friction clutch for the trolley drum, and the other the trolley drum brake. As here shown, the friction band lever 21 of the trolley drum is connected to the piston rod 25 of the air cylinder 20 while the drum friction clutch lever 23 is connected to the piston rod 24 of the air cylinder 22. Each of these air 85 cylinders 20 and 22 is connected to a compressed air tank 38 or other source of compressed air through the pipe d, which first passes from the tank through the controlling 90 valves B and B' located as here shown in 95 the horizontal operating levers A and A' and thence to the cylinders through the supply pipes 34 and 35. Thus it will be seen that each friction of the trolley drum is controlled by an air valve located in one of 100 the horizontal levers by which the main drum frictions are controlled and these air valves are operated as here shown by means located on the handles of said horizontal 105 lever as hereinafter shown.

In Figs. 2, 3 and 4 are shown the details of the horizontal levers with their connecting parts. As here shown, the levers A and A' are journaled by means of trunnions in suitable standards and just far enough apart 110 so that a man can stand between the handles and bring each within easy reach of his hands and so that each lever may be worked by bearing down with one hand or the other. The two levers are shown in Fig. 3 and similar parts in each lever are similarly lettered. At the point where the trunnions are located, there is an enlargement B which is hollow and forms an elongated valve chamber, openings being formed through 115 each trunnion connecting with the inside of the valve chamber. A cover or plate b' closes the top of the valve chamber B. At the rear (right hand as viewed in Fig. 2) 120 end of the lever there is an extension b to which is pivoted the vertical connecting rod C', the lower end of which connects with the lever C journaled to a suitable standard and having its end at a considerable distance horizontally away from the standard 125 130

so that an upward pull on the lever C will rotate the lever in its bearing. Connected with the lever C near its fulcrum is the connecting rod 17 already described which operates the main drum friction. Thus the leverage of the lever A is compounded and an increased pull exerted on the rod 17 and the lever A is thus operated with the relatively little force or weight applied to it.

10 Compressed air is supplied to both valve chambers through the pipe d (Fig. 3) which connects with a source of air supply, thence passing through pipes d' and the adjacent trunnions into the valve chamber, which is 15 kept at all times filled with air under compression. Air passes out of the chamber to the service pipe 35 on one side and 34 on the opposite side through a port b² formed in the bottom of the valve chamber near its 20 rear end and connecting through a passage-way formed in the body of the casing with the opening b⁷ through the trunnion. A vent or discharge port b³ for charging the air in the service pipe and the air cylinder 25 into the atmosphere is formed through the bottom of the air chamber adjacent to and forward of the port b². A slide valve is provided for opening the port b² and connecting the valve chamber with the service 30 pipe and for closing it and exhausting the contents of the service pipe. The valve has a flange b⁵ resting on the seat or bottom of the chamber adjacent to the port b² and adapted to cover and uncover it, and a like 35 flange b⁹ on the opposite side of the port b³, these two flanges being connected by a horizontal web b⁶ which forms beneath it a passage for the discharge of air from the port b² to the port b³ when the valve is in its 40 rear position. Upright flanges b⁴ fit loosely in the valve chamber and form guides by which it is connected with the valve stem a which extends longitudinally through the lever proper to the handle thereof. The 45 valve stem is operated and the valve moved forward and back by a grasping device, herein in the form of a longitudinal movable sleeve a² which fits over the handle and is adapted to slide lengthwise thereon. A 50 pin a' connects the sleeve with the valve stem a, a slot being formed in the handle to allow the pin to move. Suitable stuffing boxes are provided where the air pipes pass through the bearings and where the valve 55 stem passes out of the valve chamber. It will be seen that when the sleeve is in its forward (left hand as viewed in Fig. 2) position, the flange b⁵ is between the ports b² and b³ and the air from the valve chamber is free to pass out through the port and into the service pipe whereby one or the other of the air cylinders is operated. At the same time the port b³ is between the two flanges b⁵ and b⁷ and shut off from the air 60 in the chamber. When the sleeve and the

valve are pushed back (or to the right as viewed in Fig. 2), the flange b⁵ passes over the port b², shuts it off from the air in the chamber and connects it with the exhaust port b³ so that the contents of the service 70 pipe is at once exhausted and the air cylinder to which it is connected releases the brake or the clutch, as the case may be.

Having thus described the construction of my apparatus, I will now describe its operation in handling the bucket: Assuming that the bucket has just been dumped on the stage and is at its upper and inner position, the operator puts his foot on the foot lever 31 and thus opens the throttle of the trolley 80 engine, at the same time drawing the sleeve on lever A forward (to the left in Fig. 2) and setting the drum clutch 43 on the trolley drum. The rope 7 will thus wind on the trolley drum and the trolley 3 will move out 85 to the desired position on the boom. The sleeve on the lever A' is then moved out (to the left in Fig. 2) setting the band friction on the trolley drum and holding the latter stationary, the trolley engine being stopped. 90 Both levers A and A' are now lifted, releasing the drum frictions on both of the main drums and allowing the bucket to revolve the drums and to fall into the hold of the vessel with its jaws open. When the bucket 95 has settled into the mass of coal, the throttle 33 is opened by pressing down on the foot lever 32, starting the main hoisting engine. The jaws of the bucket are first closed by pressing down on the lever A, throwing in 100 the friction on the drum 12 and taking in the opening and closing rope. Both levers are then pressed down applying the drum frictions of both drums 11 and 12 and winding up on the lifting rope 5 and the closing 105 rope 6. As the bucket comes up, both the trolley drum friction and the trolley band friction are released by sliding inward (to the right in Fig. 2) the sleeves on both levers, and the trolley drum being thus free 110 to revolve, the trolley will move inward owing to the inclination of the main hoisting ropes and the tendency of the weight of the bucket to pull the trolley inward. When the bucket is at its inward position over the 115 stage, the drum 12 is released and the rope 6 loosened so that the jaws of the bucket will separate and the load will dump. It will be seen that the six motions involved are 120 easily controlled by one man since each hand governs two motions and each foot one. The three trolley controlling elements, to wit, the brake, the clutch and the throttle, are connected to be controlled two of them by the grasping devices and the third by the foot control lever, but these controlling members can be operated without conscious effort on the operator's part and without diminishing the effectiveness of his simultaneous control 125 over the bucket. The fact that both sleeves 130

are moved inward at the same time the bucket is moving in the same direction, makes the system easy to learn for a green man, and outside of the manipulation of 5 these sleeves it is worked in the same way as the old hoisting apparatus.

While I have herein shown and described for purposes of illustration one specific embodiment of the invention, it is to be understood that the same is not limited to the specific form or arrangement of parts or the constructional details thereof, or the specific application herein made thereof, but that extensive deviations may be made from the 10 disclosure herein without departing from the spirit thereof.

I claim:

1. In a hoisting apparatus, the combination of a main drum, a friction device therefor, a hand lever for operating said friction device, a trolley, a motor for controlling the rearward motion of the same, a valve for controlling said motor, and a handle for controlling said valve mounted on said lever and arranged to move longitudinally thereof.

2. In a hoisting apparatus, the combination of a main drum, a friction device therefor, a hand lever for operating said friction device, a trolley, a motor for controlling the rearward motion of the same, a valve located on said lever for controlling said motor, and a handle mounted on said lever and arranged to move longitudinally thereof.

3. In an apparatus for effecting the co-operating movements of a hoisting bucket and its traversing support, the combination of an operating rope leading to the bucket, a traversing rope leading to the support, a 30 lever for controlling the bucket rope, and a manually graspable control element having a sliding movement on said lever for the traversing rope.

4. In an apparatus of the class described, the combination with a hoisting bucket, of a bucket operating lever, and a manually graspable control element having a sliding movement on said lever for the bucket traverse.

5. In a hoisting apparatus, a one-man control device for effecting the co-operating movements of a hoisting bucket and its traversing support, comprising a bucket, a bucket motor, a pair of bucket ropes, winding drums and frictions therefor, friction controlling hand levers, said levers being located side by side at the operator's stand, a traversing support for the bucket, a traversing rope, a rope winding drum therefor, a traversing motor for turning the drum, and traversing control devices at the bucket operator's position including a movable controlling sleeve on a friction-controlling hand lever whereby the co-operating movements 60 of the bucket and its traversing support

are simultaneously controlled by the same operator.

6. In a hoisting tower, the combination with a hoisting bucket of a bucket engine, a pair of bucket ropes, winding drums and frictions therefor, friction-controlling hand levers directly and mechanically connected to control said bucket frictions, the said levers being located at the operator's position side by side with an intermediate space 70 for the operator, controlling means for the engine also at the operator's position, a traversing support for the bucket, a traversing rope, a rope winding drum therefor, a pressure fluid engine for turning the drum, and traversing control devices at the operator's position including an independently movable grasping device on each of said friction-controlling hand levers, said devices being connected to control the traverse of 80 said bucket whereby the co-operating movements of the bucket and its traversing support are simultaneously controlled by the same operator.

7. In a hoisting tower, the combination with a hoisting bucket of a bucket engine, a pair of bucket ropes, winding drums and frictions therefor, friction-controlling, hand levers directly and mechanically connected to control said frictions, the said levers being located at the operator's position side by side with an intermediate space for the operator, controlling means for the engine also at the operator's position, a traversing support for the bucket, a traversing rope, a rope winding drum therefor, a pressure fluid engine for turning the drum, and traversing control devices at the bucket operator's position including a pair of members connected one to each of said friction-controlling, hand levers, and adapted to be moved by the hands of the operator while holding said levers, said members being connected to control the traverse of the bucket whereby the co-operating movements of the bucket and its traversing support are simultaneously controlled by the same operator.

8. In a hoisting tower, the combination with a hoisting bucket of a bucket engine, a pair of bucket ropes, winding drums and frictions therefor, friction-controlling, hand levers directly and mechanically connected to control said frictions, the said levers being located at the operator's position side by side with an intermediate space for the operator, controlling means for the engine also at the operator's position, a traversing support for the bucket, a traversing rope, a rope winding drum therefor, a pressure fluid engine for turning the drum, and traversing control devices at the bucket operator's position including a member connected to a friction-controlling hand lever and adapted to be moved by the hand of the operator while holding said lever, said member being 120

connected to control the traverse of the bucket whereby the coöperating movements of the bucket and its traversing support are simultaneously controlled by the same operator.

5 9. In a hoisting tower, the combination with a hoisting bucket of a bucket engine, a pair of bucket ropes, winding drums and frictions therefor, friction-controlling hand levers for said frictions, the said levers being located at the operator's position side by side with an intermediate space for the operator, controlling means for the engine also at the operator's position, a traversing support for the bucket, a traversing rope, a rope-winding drum therefor, a pressure-fluid engine for turning the drum, and traversing control devices at the bucket operator's position including an independently 10 movable grasping device on each friction-controlling hand lever, said devices being connected to control the traverse of said bucket whereby the coöperating movements of the bucket and its traversing support are simultaneously controlled by the same operator.

10 10. In a hoisting tower, the combination with a hoisting bucket of a bucket engine, a pair of bucket ropes, winding drums and frictions therefor, friction-controlling, hand levers for said frictions, the said levers being located at the operator's position side by side with an intermediate space for the operator, controlling means for the engine also 15 at the operator's position, a traversing support for the bucket, a traversing rope, a rope-winding drum therefor, a pressure-fluid engine for turning the drum, and traversing control devices at the bucket operator's position including an independently movable grasping device on a friction-controlling hand lever connected to control the traverse of said bucket whereby the coöperating movements of the bucket and its traversing support are simultaneously controlled by the same operator.

15 11. In a hoisting tower, the combination with a hoisting bucket of a bucket engine, a pair of bucket ropes, winding drums and frictions therefor, friction-controlling hand levers directly and mechanically connected to control said bucket frictions, the said levers being located at the operator's position side by side with an intermediate space for the operator, controlling means for the engine also at the operator's position, a traversing support for the bucket, a traversing rope, a rope winding drum therefor, a pressure fluid engine for turning the drum, a throttle for said pressure fluid engine, a 20 brake for said traversing rope winding drum, and traversing control devices at the operator's position including an independently movable grasping device on one of said friction-controlling hand levers connected to control said brake and a similar device on said second friction controlling hand lever connected also to assist in the control of the traverse of said bucket, whereby the coöperating movements of the bucket and its traversing support are simultaneously controlled by the same operator.

20 12. In a hoisting tower, the combination with a hoisting bucket of a bucket engine, a pair of bucket ropes, winding drums and frictions therefor, friction-controlling hand levers directly and mechanically connected to control said frictions, the said levers being located at the operator's position side by side with an intermediate space for the operator, controlling means for the engine also at the operator's position, a traversing support for the bucket, a traversing rope, a rope winding drum therefor, a pressure fluid engine for turning the drum, a throttle for said pressure fluid engine, a 25 brake for said traversing rope winding drum, and traversing control devices at the operator's position including a foot-operated control element, and a grasping device on and independently movable of each

of said friction controlling hand levers, said devices and said foot-controlling element being connected to control the traversing of said bucket whereby the coöperating movement of the bucket and its traversing support are simultaneously controlled by the same operator.

25 12. In a hoisting tower, the combination with a hoisting bucket of a bucket engine, a pair of bucket ropes, winding drums and frictions therefor, friction-controlling hand levers directly and mechanically connected to control said frictions, the said levers being located at the operator's position side by side with an intermediate space for the operator, controlling means for the engine also at the operator's position, a traversing support for the bucket, a traversing rope, a rope winding drum therefor, a pressure fluid engine for turning the drum, and traversing 30 control devices at the bucket operator's position including a foot-operated control element and a member connected to a friction controlling hand lever and adapted to be moved by the hand of the operator while holding said lever, said foot-operated control element and said member being connected to control the traverse of the bucket whereby the coöperating movements of the bucket and its traversing support are simultaneously controlled by the same operator.

35 13. In a hoisting tower, the combination with a hoisting bucket of a bucket engine, a pair of bucket ropes, winding drums and frictions therefor, friction-controlling hand levers directly and mechanically connected to control said bucket frictions, the said levers being located at the operator's position side by side with an intermediate space for the operator, controlling means for the engine also at the operator's position, a traversing support for the bucket, a traversing rope, a rope winding drum therefor, a pressure fluid engine for turning the drum, a throttle for said pressure fluid engine, a 40 brake for said traversing rope winding drum, and traversing control devices at the operator's position including an independently movable grasping device on one of said friction-controlling hand levers connected to control said brake and a similar device on said second friction controlling hand lever connected also to assist in the control of the traverse of said bucket, whereby the coöperating movements of the bucket and its traversing support are simultaneously controlled by the same operator.

45 14. In a hoisting tower, the combination with a hoisting bucket of a bucket engine, a pair of bucket ropes, winding drums and frictions therefor, friction-controlling hand levers directly and mechanically connected to control said frictions, the said levers being located at the operator's position side by side with an intermediate space for the operator, controlling means for the engine also at the operator's position, a traversing support for the bucket, a traversing rope, a rope winding drum therefor, a pressure fluid engine for turning the drum, a throttle for said pressure fluid engine, a 50 brake for said traversing rope winding drum, and traversing control devices at the operator's position including a foot-operated control element, and a grasping device on and independently movable of each

erator, controlling means for the engine also at the operator's position, a traversing support for the bucket, a traversing rope, a rope-winding drum therefor, a pressure fluid

5 rope winding drum therefor, a pressure fluid engine for turning the drum, a throttle for said pressure fluid engine, a brake for the traversing rope winding drum and traversing control devices at the bucket operator's position, including a member connected to

10 a friction-controlling hand lever and adapted to be moved by the hand of the operator while holding said lever, said member being connected to control the traverse of the bucket whereby the co-operating movements
15 of the bucket and its traversing support are simultaneously controlled by the same operator.

15. In a hoisting tower, the combination with a hoisting bucket of a bucket engine, a 20 pair of bucket ropes, winding drums and frictions therefor, friction-controlling hand levers directly and mechanically connected to control said frictions, the said levers being located at the operator's position side by 25 side with an intermediate space for the operator, controlling means for the engine also at the operator's position, a traversing support for the bucket, a traversing rope, a rope-winding drum therefor, a pressure fluid 30 engine for turning the drum, a throttle for

39 engine for turning the drum, a throttle for said pressure fluid engine, a brake for the traversing rope winding drum and traversing control devices at the bucket operator's position, including a pair of members con-

35 nected one to each of said friction-controlled hand levers, and adapted to be moved by the hands of the operator while holding said levers, said members being connected to control the traverse of the bucket, whereby the
40 co-operative movements of the bucket and its traverse support are simultaneously controlled by the same operator.

16. In a hoisting tower, the combination

45. In a hoisting tower, the combination with a hoisting bucket of a bucket engine, a pair of bucket ropes, winding drums and frictions therefor, friction-controlling hand

levers directly and mechanically connected to control said bucket frictions, the said levers being located at the operator's position side by side with an intermediate space for

the operator, controlling means for the engine also at the operator's position, a traversing support for the bucket, a traversing rope, a rope-winding drum therefor, a pres-

55 sure fluid engine for turning the drum, a throttle for said pressure fluid engine, a brake for said traversing rope winding drum, a pressure fluid device for moving the brake, a valve for controlling the pressure

60 said a valve for controlling the pressure fluid device, and traversing control devices at the bucket operator's position including a throttle control device and a grasping device for controlling said valve mounted on

65 for controlling said valve mounted on and independently movable of one of said friction-controlling, hand levers, whereby

the coöperating movements of the bucket and its traverse support are simultaneously controlled by the same operator.

17. In a hoisting tower, the combination with a hoisting bucket of a bucket engine, a pair of bucket ropes, winding drums and frictions therefor, friction-controlling, hand levers directly and mechanically connected to control said bucket frictions, the said levers being located at the operator's position side by side with an intermediate space for the operator, controlling means for the engine also at the operator's position, a traversing support for the bucket, a traversing rope, a rope winding drum therefor, a pressure-fluid engine for turning the drum, and three traversing control elements having traversing control devices at the bucket operator's position, said devices including an independently movable grasping device on each of said friction-controlling hand levers for two of said traversing control elements, and a third device also at the bucket operator's position for said third traversing control element, said devices being connected to control the traverse of said bucket, whereby the coöperating movements of the bucket and its traversing support are simultaneously controlled by the same operator. 70 75 80 85 90

13. In a hoisting tower, the combination 95
with a hoisting bucket of a bucket engine, a
pair of bucket ropes, winding drums and
frictions therefor, friction-controlling hand
levers directly and mechanically connected
to said frictions, the said levers being located
at the operator's position side by side with
an intermediate space for the operator, controlling
means for the engine also at the
operator's position, a traversing support for
the bucket, a traversing rope, a rope winding
drum therefor, a pressure fluid engine for
turning the drum, and three traversing control
means including a throttle for the said
pressure fluid engine, and a brake for the
traversing winding drum, said means having
traversing control devices at the bucket
operator's position, including a member for
controlling the brake connected to one of
said friction-controlling hand levers, and a
member for controlling a second one of said
traversing control means connected to the
second one of said friction-controlling hand
levers, said members being adapted to be
moved by the hands of the operator while
holding said levers, and a controlling device
for said third traversing control means also
at the operator's position, whereby the co-
operating movements of the bucket and its
traversing support are simultaneously con-
trolled by the same operator. 100
105
110
115
120
125

19. In a hoisting tower, the combination with a hoisting bucket, of a bucket motor, a pair of bucket ropes, winding drums and frictions therefor, friction controlling hand levers directly and mechanically connected 130

to said frictions said levers being located at the operator's stand side by side, a traversing support for the bucket, a traversing rope, a rope-winding drum therefor, a traversing motor for turning said drum, a starting device for the traversing motor, a brake for the traversing rope drum and traversing control devices for said starting device and brake also at the operator's stand and adapted to be controlled by the operator while maintaining his hold upon the bucket levers, said devices including an independently

movable grasping device upon a friction controlling hand lever whereby the coöperating movements of the bucket and its traversing support are simultaneously controlled by the same operator.

Signed by me at Portland, Maine, this 22d day of December, 1906.
